UNITED STATES PATENT OFFICE

ALVA M. HULL, OF DETROIT, MICHIGAN, ASSIGNOR TO HUL-LO-WEN FIREPROOF EVER-LASTING HOMES COMPANY, OF DETROIT, MICHIGAN, A CORPORATION OF MICHIGAN

BUILDING CONSTRUCTION

Original application filed August 30, 1926, Serial No. 132,340. Divided and this application filed October 17, 1928. Serial No. 312,975.

The present invention relates to building construction and more particularly to methods of and means for constructing buildings quickly and efficiently.

Among the objects of the invention is to simplify the erection of buildings of all sorts and yet produce a structure which is permanent.

Another object is the production of a building structure which shall be fireproof, vermin proof, and resistant to heat transfer through its elements.

Other objects will readily appear to those skilled in the art upon reference to the following description and drawing in which Figure 1 is a perspective view of a door unit used in such construction. Fig. 2 is a section on line 2—2 of Fig. 1 and Fig. 3 is a section on line 3—3 of Fig. 1.

The present application is a division of application Ser. No. 132,340 filed Aug. 30, 1926.

In the drawing a foundation wall 10 is shown as having a channel member 50 secured thereon and secured therein, as by screws 80, upright channel members 20 and 83. The members 20 may be portions of wall construction units such as are described in the case referred to or single channel members, if the location of the door unit does not permit use of such a wall unit.

The door unit is preferably positioned between two upright members 20 secured to channels 50 as mentioned above and secured together at the top by a cross member 22 and near the top by a cross channel 81 welded, bolted or otherwise secured to the members 20. Over member 22 is placed the channel 52 and is secured by clips 51 and 61. Cross channel 81 is located at a point somewhat above the door height and is provided with bolt holes 82, there being several in each flange as shown, to permit the location of the door frame proper or to accommodate frames of different widths.

The inner door or frame proper consists of two upright channel members 83 and a cross member 84 bolted thereto near the top as at 35, these members may be provided with spines 27 as shown. Between channels 81

and 22 it is preferred to insert bracing members 20a and 20b, to provide vertical and diagonal bracing and support for the upper end of the unit. At the lower ends, the members 83 will be bolted to channel 50 as indicated and the flanges of the latter cut and flattened down as at 86. Each of the members 83 is preferably provided on its web portion with the angle members 88 welded thereto and provide the member 83 with additional flanges spaced from each other somewhat more than the width of the channel. The member 84 is similarly provided with such angle members so that the molding forming the door jamb may be formed to fit either within or on the outside of these flanges 88 being held therein or thereon in any suitable manner. The shoulder 89 formed by the back surface of the angle projecting beyond the channel member 83 forms a convenient means for determining the thickness of the wall surfacing material such as plaster, this angle member being used as a guide for the troweling of the plastic material.

The door unit is designed to be used with the wall construction described in the parent case and for this reason is shown as provided with the spines 27 for attachment of insulation and metal lath in the manner therein described.

Having now described the invention and the preferred form of embodiment thereof, it is to be understood that the said invention is to be limited, not to the specific details herein set forth and illustrated but only by the scope of the claims which follow.

I claim:

1. In wall construction for buildings in which a plurality of similar wall units are used, a door unit comprising side members similar in form to the side members of the units, a top cross member similar in form to the top members of the units, a second cross member near the said top member secured to said side members of the door unit, said second cross member being provided with a plurality of spaced bolt or screw holes near its ends and a door frame adapted to be bolted to said second cross member, said plurality of holes permitting selection of one of

several different lateral positions for said door frame, said holes also permitting the use of any one of several widths of door frames.

- 5 2. In wall construction for buildings in which a plurality of similar wall units are used, a door unit comprising side members similar in form to the side members of the units, a top cross member similar in form to
- 10 the top members of the units, a second cross member near the said top member secured to said side members of the door unit, said second cross member being provided with a plurality of spaced bolt or screw holes near its ends, a door frame adapted to be bolted to said second cross member and diagonal bracing structure between said top member and said second cross member.
- 15 3. In wall construction for buildings in which a plurality of similar wall units are used, a door unit comprising an outer frame similar in form to the frames of the units, a horizontal cross member inside and secured to said outer frame, a door frame within the
- 20 outer frame and under the cross bar, and means engaging and connecting the door frame and the cross member to secure the former to the latter, the means being adjustable so that the position of the door frame in
- 25 the outer frame may be varied as the former is suspended from the latter.

ALVA M. HULL.
